UNITED STATES PATENT OFFICE.

JOHN STAUNTON KING, OF TORONTO, CANADA.

HOCKEY-BOOT.

No. 806,267.

Specification of Letters Patent.

Patented Dec. 5, 1905.

Application filed February 13, 1905. Serial No. 245,520.

To all whom it may concern:

Be it known that I, JOHN STAUNTON KING, of the city of Toronto, in the county of York, in the Province of Ontario, Canada, have invented certain new and useful Improvements in Hockey-Boots, of which the following is a specification.

My invention relates to improvements in hockey-boots; and the object of the invention is to devise a strong durable boot of this class by which the instep and toe of the wearer may be efficiently protected; and it consists, essentially, of a boot provided with a reinforced lacing and a supplemental lace fastening or flap attached to the outside of the ordinary facing, a toe-cap provided with a rearwardly-extending portion, and a protecting-tongue preferably secured to the rear end of such toe-cap and extending between the supplemental lace-facing when the boot is laced, the parts being otherwise arranged and constructed as hereinafter more particularly explained.

Figure 1 is a perspective view of a boot constructed in accordance with my invention. Fig. 2 is a longitudinal section of the boot. Fig. 3 is a cross-section on the line xy , Fig. 2.

In the drawings like letters of reference indicate corresponding parts in each figure.

A is the upper of my improved hockey-boot, which is provided on the interior with the diagonally-arranged reinforcing strips of leather, canvas, or other suitable material aa' .

A' represents reinforcing-strips secured within the ordinary lace-facing A^2 and designed to strengthen such facing and the holes therein. The facing extends down to the toe portion, as indicated.

B is my supplemental lace facings or flaps, which are suitably sewed on at the outside of the ordinary lace-facing.

C is the toe-cap, which is provided with a rearwardly-extending portion c , which extends between the lower ends of the supplemental lace-facing.

D is a supplemental tongue, which is padded or made pneumatic or constructed of any suitable material which will be soft and resilient. The tongue D when the boot is laced extends between the supplemental lace-facings B, the laces of which extend over the tongue D.

I of course provide also in addition to the tongue D the ordinary tongue E, which extends inside of the reinforcing-strips A' of the ordinary lace-facing.

55

The boot is first laced up through the ordinary lace-facing in the usual manner. The tongue D is then drawn down and the supplemental laces are laced up through the supplemental lace-facing B, holding the tongue D down in position, and thereby providing a soft protecting strip or pad, which with the reinforcement of the ordinary lace-facing effectually protects the instep of the wearer from abrasion or injury by a hockey-stick or otherwise.

60 What I claim as my invention is—

1. In a hockey-boot, the combination with the upper provided with the ordinary facings, of a toe-cap and protecting strip or tongue attached to the rear of the toe-cap and extending in front of the ordinary lace-facings as and for the purpose specified.

65 2. In a hockey-boot, the combination with the upper provided with the ordinary lace-facings, of a toe-cap provided with a rearwardly-extending portion and a protecting strip or tongue attached to the rear of such portion and extending in front of the ordinary lace-facings as and for the purpose specified.

70 3. In a hockey-boot, the combination with the upper provided with the ordinary lace-facings, of supplemental lace-facings secured at the outside of the lace-facings and a protecting strip or tongue secured to the front of the boot and extending between the supplemental lace-facings and held therebetween by the laces as and for the purpose specified.

75 4. In a boot, the combination with the upper provided with the ordinary lace-facing, a toe-cap having a projecting rear portion, a protecting pad or tongue secured to said portion and the supplemental lace-facings between which and the ordinary lace-facings the said pad or tongue fits.

JOHN STAUNTON KING.
